UNITED STATES PATENT OFFICE.

NORMAN N. GORDON, OF ROCHESTER, NEW YORK, ASSIGNOR OF ONE-HALF
TO RUDOLPH LICHTENSTEIN, OF SAME PLACE.

FOLDING TABLE.

SPECIFICATION forming part of Letters Patent No. 316,142, dated April 21, 1885.

Application filed May 8, 1884. (No model.)

To all whom it may concern:

Be it known that I, NORMAN N. GORDON, of 5
Rochester, in the county of Monroe and State
of New York, have invented a new and useful
Improvement in Folding Tables, which im-
provement is fully set forth in the following
specification and accompanying drawings.

The object of my invention is to produce a
cheap wooden table for use on lawns, picnic
10 and pleasure grounds, in kitchens, and work-
shops, &c., said table being constructed with
a folding top, which, when folded or closed, con-
stitutes a close box, in which to contain the
removable legs and other detachable parts of
15 the table, thus forming altogether a convenient
package for handling, storing, and transpor-
tation; and the invention consists of parts con-
structed and combined as hereinafter fully de-
scribed, and more particularly pointed out in
20 the claim.

Referring to the drawings, Figure 1 is an
end elevation of the table with the crossed legs
25 in place under the folding top board; Fig. 2,
a side elevation of the same, showing more
clearly the tie-rod for the legs. Fig. 3 shows
the under side of the top board of the table
30 with the legs and tie-rod taken down and placed
in the hollow or cavity of the top board. Fig.
4 shows the whole when packed and folded for
storage or transportation; and Fig. 5, drawn to
35 a larger scale, shows the manner in which the
upper points of the legs are formed and se-
cured to the top board of the table.

Referring to the figures, A is the top board
35 of the table, which is divided longitudinally
into two parts, b and d, along the line a, said
parts being joined by flexible hinges c c, per-
mitting the parts b and d to be folded upon
40 each other or closed, as shown in Fig. 4. Each
of the parts b and d of the top board is formed
with a cavity or hollow, g. As shown in the
drawings, each of these cavities is formed by
securing strips of wood or rails i, of equal
45 width and thickness, at the edges of and to the
under side of the thin board f, which forms
the upper part or member of the top board of
the table. The cavities g g are formed in the
parts b and d of the top board, so as to regis-

ter and form a single symmetrical cavity or in-
terior of the box when the parts are folded, 50
as above stated.

The legs h consist of four strips of wood,
beveled at their ends and made to cross each
other in pairs under the top board of the ta-
ble in a manner that is common. The upper 55
ends of the legs support the top of the table
and the lower ends rest upon the ground with
a longitudinal tie-rod, k, passing through the
legs at the points at which they intersect each
other in pairs. 60

The tie-rod I prefer to make of gas-pipe, for
the sake of lightness, and it may be secured to
the legs in any convenient manner. As shown,
the ends of the pipe are threaded to receive
thumb-screw nuts e e, which, when turned for-
ward, press the respective pairs of legs against
65 fixed collars n on the pipe. The upper ends
of the legs I prefer to provide with metal tips
o, as shown in Fig. 5, the points of which en-
ter cavities or rests r, Fig. 3, formed in the 70
rails i of the top board beneath simple plates
s, embedded in the rails in position to cover
said cavities, one of which plates being omit-
ted from Fig. 3 to expose the cavity beneath.
The tips o of the legs fit snugly in the respect-
75 ive cavities or rests r under the plates there-
of, and when the legs are thus put in place
and the thumb-nuts set tightly against them,
as above specified, they are held firmly to-
gether, rendering the whole table compara-
80 tively strong and unyielding. Simple longi-
tudinal braces to stiffen the table may be in-
serted, if necessary, having bearings against
the rails of the top board of the table and the
legs. 85

The dimensions of the legs, tie-rod, and
other detachable parts of the table are such
that they all may be inclosed in the space g of
the top board, A, as shown, and the top board
folded into a convenient package or box to in-
close said loose parts, and locked, as repre-
sented in Fig. 4, for storing, handling, or
transportation.

A simple transverse rod, p, passed through
the rails in holes u under the boards f, as shown,
95 prevents the parts b and d of the table from

folding when the latter is erected for use. This rod is withdrawn and placed in the box formed by the folded parts *b* and *d* of the table with the other detachable parts when the 5 table is taken down and packed for storing or transportation.

What I claim as my invention is—

A folding table having the top board divided longitudinally along its center, and provided with strips *i*, secured to the under surfaces of the two parts of the top board along the sides and ends thereof, the two parts being joined by hinges at the line of division

for the purpose of folding, said strips *i* at the two outer sides of the top board being provided with recesses *r* and metal plates *s*, in combination with cross-legs *h*, for supporting the table, provided with metal tips *o* at their upper ends, formed to enter said recesses *r*, and a cross-bolt, *p*, passed transversely through 20 the strips *i*, all combined and arranged substantially as shown and described.

NORMAN N. GORDON.
